UNITED STATES PATENT OFFICE.

JOEL D. BARBER, OF BRONXVILLE, NEW YORK.

AUTOMATON-FIXTURE.

1,263,838.

Specification of Letters Patent. Patented Apr. 23, 1918.

Application filed July 26, 1916. Serial No. 111,512.

To all whom it may concern:

Be it known that I, JOEL D. BARBER, a citizen of the United States, residing at Bronxville, in the county of Westchester 5 and State of New York, have invented new and useful Improvements in Automaton-Fixtures, of which the following is a specification.

This invention relates to an automaton fixture adapted to be attached to water spigots and to be actuated by the flow of water therefrom. The fixture or attachment of my invention is constructed primarily to contribute a novel ornamental value to the 15 bath room when associated with the bath fixtures and further to be pleasing in its action. Moreover, the device of my invention is beneficial in that it is particularly attractive to children possessing additional 20 value to its ornamental effect aforesaid.

The device of my invention is shown in the accompanying drawing wherein the reference characters of this description are applied to the corresponding parts in the 25 several views.

Referring to the drawing, Figure 1 is a view in side elevation illustrating a desirable embodiment of my invention. Fig. 2 is an end elevation thereof and Fig. 3 illustrates a desirable modified form thereof.

As illustrated the body member 1 of my device is of a form to resemble a living being or to outline the form thereof and may desirably be cut out of wood and then 35 painted in suitable manner to further the effect. A passage or duct 2-3 is formed therein to extend through the body from the top to the bottom and the body member is provided with suitable means for attaching 40 it to the spigot of water fixtures. As shown it is here provided with a rubber gasket attachment member 4 having a rubber gasket 5 adapted to detachably secure the device in position. While I have shown my device 45 arranged to be detachably secured in position it will be readily understood that it may be made of metal and as a permanent part of the water fixture.

To produce the animated effect desired I 50 have arranged a rotor element 7, having marginal pockets 8 formed therein, journaled in position to be rotated by the contact of the water therewith as it flows through the passage 2-3. In Fig. 1 the rotor 7 is 55 journaled at 10 in supporting and adjusting members 11-11, the latter being pivoted to

the body member by means of a pin 12. At their upper ends the adjusting members are joined by means of a spreader of cross rod 14 which is received within a groove 15 in the upper surface of the body portion. By this arrangement it will be seen that when the rotor is in its forward position the rotor, journaled on pin 10, will be supported to one side of the vertical plane of pin 12 and 60 in position to have movement imparted thereto by the flow of water. When moved to the retracted position shown in dotted lines, the journal bearing of the rotor will be seen to be to the opposite or right hand 65 side of the vertical plane of pivotal point 12 and the rotor will then be in an inoperative position. The groove 15 properly limits the movement of the adjusting members and as 70 will be readily understood, by reason of the 75 shifting of the journal pin 10 of the rotor from one side to the other of the pivotal point of the adjusting members, considered with reference to the vertical plane, these members will remain in the positions indicated without requiring special retaining 80 means therefor.

As shown in Figs. 1 and 2, the rotor is provided on its opposite faces with eccentric members 18-18 by means of which movement of the rotor may be communicated to other parts to produce additional motion when desired. As indicated, it is arranged that each eccentric shall actuate a foot element 20 supported upon a supporting or 85 leg wire 21 bent to encircle the eccentrics at their upper ends and passed through an opening 22 in the body portion the walls thereof acting as fulcrums to determine the movement imparted by the eccentrics. 90

In the modified form shown in Fig. 3 I have provided an additional rotor element 24 positioned in the path of the flow of water thus providing for additional movement being communicated directly by the 100 action of the water.

While I have shown and described a desirable embodiment of my invention, it will be understood that my invention is capable of varied modification without departing 105 from the scope of the appended claims and it is therefore intended that all matter contained herein shall be interpreted as illustrative and not in a limiting sense.

Having described my invention I claim,

1. An automaton device of the character described comprising a body member having

- 2
- 5 a passage therein, adjustable supporting means pivoted to the body member, a rotor journaled in said supporting means, means to limit the movement of said adjustable means and said means being operative to shift said rotor into inoperative and operative position and to shift past center with reference to the pivotal point of said supporting means, substantially as described.
- 10 2. An automaton device of the character described comprising a body member having a passage therein, adjustable supporting members pivoted to the body member, a ro-

tor journaled in said supporting members, a spreader member connecting the supporting members at their upper ends and arranged to move in a confining slot in the body member, eccentrics carried by the rotor, movable members and supporting connections from the eccentrics to said movable members to actuate and support the latter substantially as described. 15

In testimony whereof I have signed my name to this specification.

JOEL D. BARBER.
